ALBERT J. D. OHM, OF NEW YORK, N. Y., ASSIGNOR TO LION ELECTRIC APPLIANCE CO., INC., OF NEW YORK, N. Y., A CORPORATION OF NEW YORK.

DESIGN FOR A LIGHTING-FIXTURE BRACKET-BACK.

57,254.

Specification for Design.

Patented Mar. 8, 1921.

Application filed August 20, 1920. Serial No. 404,927. Term of patent 3½ years.

To all whom it may concern:

Be it known that I, ALBERT J. D. OHM, residing at 133 Steinway avenue, Astoria, in the borough of Queens, city and State of New York, and a citizen of the United States, have invented a new, original, and ornamental Design for Lighting-Fixture Bracket-Backs, of which the following is a specification, reference being had to the accompanying drawing, forming part thereof.

The figure shows a plan view of a bracket back, showing my new design.

I claim:

The ornamental design for a lighting fixture bracket back, as shown.
